UNITED STATES PATENT OFFICE.

FRANKLIN S. SMITH, OF PHILADELPHIA, PENNSYLVANIA.

PNEUMATIC-DESPATCH APPARATUS.

No. 816,262.

Specification of Letters Patent.

Patented March 27, 1906.

Application filed June 28, 1905. Serial No. 267,404.

To all whom it may concern:

Be it known that I, FRANKLIN S. SMITH, a citizen of the United States, residing in the city and county of Philadelphia, State of Pennsylvania, have invented certain new and useful Improvements in Pneumatic-Despatch Apparatus, of which the following is a description.

My invention relates to improvements in pneumatic despatch apparatus, and it has for its specific object the provision of an improvement in the means by which a valve or other obstruction extending across a discharge opening provided in such an apparatus is prevented from being opened, or is permitted to be opened by the impact of a carrier passing through the apparatus, to prevent or to permit, as desired, the discharge of the said carrier from the said apparatus.

By the employment of my improvement for the purpose just specified, I am enabled to continue the curvature of the terminal portions of the passageway of the apparatus at the sub-stations to points including and beyond the discharge opening of the terminal, and thus decrease the length and consequently the amount of material constituting the terminal.

In the accompanying drawing forming a part of this specification, I have illustrated a convenient form of embodiment of my invention, though it will be understood that various changes in the matter of details may be made without departing from the scope of my invention.

In the drawings,

Figure I is a side elevation of a pneumatic despatch apparatus with portions of the intermediate or sub-stations removed, so as to show more clearly the mechanism of such terminals.

Figure II is a view in reversed position of a portion of the terminal shown at the middle of figure I with certain parts removed, the valve being shown in section, and also showing one form of carrier in transit through the said terminal.

Figure III is a view similar to figure II, showing another form of carrier which is adapted to be discharged from the terminal.

Figure IV is a view of a portion of the terminal shown at the right hand side of figure I, a part of the said terminal being removed to show the mechanism of the said terminal more clearly, and showing an arrangement of catch different from that shown in figures II

and III, and showing also in dotted lines one form of carrier after it has passed beyond the discharge opening of the said terminal, and showing another form of carrier in full lines, 60 which is adapted to be discharged from said terminal.

In the form of apparatus illustrated, the passage or transit of the carriers through the despatch tube of the apparatus is occasioned 65 by the creation of a vacuum in the said tube in front of the carrier, though it is to be understood that my invention is equally applicable to a construction in which the carriers are propelled or forced through the despatch 70 tube in any other suitable manner.

Referring to the drawings,

1 designates an open-ended section of a despatch tube through which the carriers are forwarded from the central station of the apparatus. This tube is connected at one end to a sub-station terminal 2, which terminal is connected to a second sub-station terminal 3 by a section 4 of the despatch tube. Each of these sub-station terminals, as will be observed, is of substantially the same construction.

The sub-station terminals are curved so that each of them constitutes the greater portion of a complete circle. Referring to the 85 terminal 2, it will be seen that it begins to curve at the point of connection of the same and the end of the section 1 of the despatch tube, and that such curvature continues to a point which is adjacent to the end of the section 1 of the despatch tube, which is connected to the said terminal, such point being beyond the discharge opening 5 of the terminal. At this point, the terminal is provided with a portion 6, which is substantially parallel with 90 an adjacent part of the end portion of the section 1 of the despatch tube, which is connected to the said terminal.

The section 6 of the said terminal constitutes the end portion thereof, which is connected at 7 to an outgoing section 4 of the despatch tube which leads from the first sub-station terminal 2 to the second sub-station terminal 3, the construction of which is in all respects similar to that of the first terminal, 105 as has been stated previously.

As illustrated in the drawings, each of the terminals consists of two sections or halves, which are semi-circular in cross section, and which are adapted to be secured together 110 by means of screws (not shown), which are adapted to engage the ears or projections 8.

When the two sections of a terminal are joined in this manner, it will be understood that in cross section such terminal is of circular outline. While I have illustrated the terminals as being constructed of two sections, as described, I do not desire to be limited to such manner of construction, as it may be found convenient and desirable to construct the terminal in some other manner, as, for instance, by casting, or otherwise forming or producing the same of a single, integral piece of material.

For the purpose of either permitting or preventing the discharge of a carrier through the discharge openings of the terminals 2 and 3, I have provided a device which extends across the said discharge opening, such device operating in the manner hereinafter set forth.

As illustrated, the said device consists of a valve which is hinged at 11, and which is provided with a spring or other suitable means (not shown) for the purpose of holding it in closed position. The said valve consists of the outer plate member 12, the inner plate or strip 13, and the intermediate member 14, of leather or other suitable material, which is adapted to rest upon the outer edges of the discharge openings 5 to close the same.

The sub-station terminal 3, illustrated in the enlarged views figures II and III, is provided with a catch 15 which is pivoted at 16 upon a pivot which is supported upon what may be termed a hollow projection 17 formed upon the side of the sub-station terminal 3.

Normally, the catch 15 is in engagement with the outer end of the plate or strip 13, as is clearly shown in figure II of the drawings, and it is held in this position by the weight or weighted end 18, which, in the drawings, is shown as being integral with the said catch. It will be understood, however, that the catch may be held in normal engagement with the said strip by any other suitable means.

20 designates a projection or finger which extends out from said catch into the passage-way of the terminal and is adapted to be engaged by a carrier of the construction of the carrier 21, shown in figures I and III, which carrier is provided with heads or enlargements 22 at its opposite ends, in the usual manner.

It will be observed that the projection or finger 20 is but slightly separated from the upper surface of the end portion of the plate or strip 13, but this separation is sufficient to permit pivotal movement of the catch 15, to disengage the same from the end of the said strip when it is engaged by the end of a carrier like the carrier 21 shown in figure III.

60 When a carrier 21 is passing through a terminal provided with a catch mechanism like that shown in figures II and III, the forward end of the same will strike the projection or finger 20 and will occasion the disengagement of the catch 15 from the outer end of

the plate or strip 13 so that when the forward end of the said carrier strikes the same plate or strip (which in the construction shown forms a part of the valve for closing the discharge openings) it will open the same and will issue from the said terminal through the discharge opening.

In figure I, within sub - station terminal 2 in figure II, and also in figure IV, I have shown a carrier 23 of a construction similar to that of the carrier 21 except that it is provided with projections 24 upon its opposite ends, the said projections being of less diameter than the enlargements or heads 25. The purpose of providing these projections is to prevent the carrier 23 from engaging with the projection or finger 20 to disengage the catch 15 from the outer end of the plate or strip 13. This is effected by reason of the fact that during the passage of a carrier 23 through a terminal provided with a catch of the construction of the catch 15, shown in figures II and III, the projection 24 upon the forward end of such carrier will strike the plate or strip 13, whereby the forward end of the said carrier will be deflected so that the enlargement or head 25 thereof would not come into contact with the projection or finger 20 to disengage the catch 15 from the said plate or strip 13. The carrier 23 not being adapted to disengage the catch 15 from the plate or strip 13, it is evident that the discharge opening would not be opened and that such carrier would be carried forward beyond such terminal.

The terminal 2 shown at the right hand side of figure I and illustrated in enlarged view in figure IV, is provided with a catch mechanism of different construction from that shown in figures II and III. In the construction of catch mechanism shown in figure IV, the catch extends or is bent in a direction opposite to that of the catch shown in figures II and III and normally is not engaged with the plate or strip 13. It is adapted, however, to engage the outer or upper edge of an opening 30 extending through the upper end of the said plate or strip.

Upon inspection of Figure IV, it will be seen that this form of catch mechanism is adapted to permit the escape or discharge of a carrier having the construction of the carrier 23. During the passage of a carrier of this construction through a terminal provided with catch mechanism such as is shown in Figure IV, the projection 24 upon the forward end of the said carrier strikes the plate or strip 13 and moves the same about its pivot so as to bring the same out of position to be engaged by the catch 29 when it is moved about its pivot by reason of the engagement of the projection or finger 20 thereof by the head 25 of the carrier 23 as it passes through the discharge opening 5.

In said Figure IV is shown in dotted lines a

carrier of the same construction as the carrier 21 shown in Figures I and III, which has just passed beyond the discharge opening 5. When a carrier constructed like that of the carrier 21 shown in dotted lines in Figure IV is passing through a terminal provided with catch mechanism like that shown in Figure IV, it will be understood that the enlargement or head upon the forward end of the carrier strikes the projection or finger 20 and moves the catch 29 into engagement with the upper edge of the opening 30 through the plate or strip 13 and thus prevents movement of the said plate or strip to open the discharge opening 5 when the forward end of the said carrier comes into engagement with the said plate or strip. The catch 29 being in engagement with the said plate or strip at the time the forward end of the said carrier comes into contact therewith, such forward end is deflected and the said carrier is compelled to continue its passage through the terminal and forward to the next or succeeding terminal, which, in the construction illustrated, is provided with a catch mechanism which is adapted to be opened by a carrier of the construction of the said carrier 21, to permit its discharge.

In order to limit the pivotal movement of the catches 15 and 29, as a result of the engagement of the projection or finger 20 with the enlargements or heads upon the carriers, the stop 31 is provided which consists of a cross piece extending from side to side of the hollow projection within which the said catches are pivoted.

The said stop or cross piece in Figure IV also serves the additional purpose of supporting the weight 18 in a proper position.

Referring to Figure I, it will be noted that the carrier 21, after having been inserted in the section 1 of the despatch tube, has passed from the same through the first sub-station terminal 2 and is in the act of being discharged from the second sub-station terminal 3, while the carrier 23 after having been inserted in section 1 of the discharge tube has just reached the discharge opening 5 of the first sub-station terminal 2 where it will be discharged.

In order to return the carriers from the sub-stations to the central station, they are inserted into the despatch tube through the openings 32 closed by the valves 33. The middle sub-station terminal 3 is connected to the central sub-station of the apparatus by means of the section of tube 35, shown in Figure I.

The subject-matter disclosed but not claimed in this application is claimed in my co-pending application, Serial No. 267,403.

Having thus described my invention, I claim—

1. A pneumatic despatch apparatus comprising a terminal having a discharge open-

ing, a device which extends across the said opening and which device is normally in a closed position, a pivoted catch normally in engagement with the said device, and means integral with the said catch which extends therefrom into the interior or passageway of the said terminal, and a carrier provided with a head upon its end which is adapted to engage the said means to occasion disengagement of the catch from the said device to permit the latter to be opened by the impact of the said carrier.

2. A pneumatic despatch apparatus comprising a terminal having a discharge opening, a device extending across the said opening, the said device being normally in a closed position, a pivoted catch normally in engagement with the said device, means extending from the said catch into the interior or passageway of the said terminal, a carrier provided with a head upon its end which is adapted to engage the said means and occasion disengagement of the catch from the said device to permit the same to be opened by the impact of the said carrier, and a second carrier provided with a projection upon its end which is adapted to strike the device extending across the said discharge opening whereby the said second carrier is adapted to be deflected so that the front portion or end thereof adjacent to the said projection is prevented from coming into engagement with the said means to occasion disengagement of the said catch from the said device.

3. A pneumatic despatch apparatus comprising a terminal having a discharge opening, a device extending across the said opening, the said device being normally in a closed position, a pivoted catch normally in engagement with the said device, means extending from the said catch into the interior or passageway of the said terminal, a carrier provided with a head or enlargement upon its end which is adapted to engage the said means and occasion disengagement of the catch from the said device to permit the same to be opened by the impact of the said carrier, and a second carrier provided with a head or enlargement upon one end, and a projection, of less diameter than the said head or enlargement, which is adapted to strike the said device extending across the said discharge opening, whereby deflection of the front or forward end of the said carrier is occasioned to prevent the said head or enlargement from engaging with the said means to disengage the said catch from the said device.

4. A pneumatic despatch apparatus comprising a terminal having a discharge opening, a device extending across the said discharge opening to close the same, a catch, means for normally holding the said catch in engagement with the said device, a projection or finger integral with the said catch and

which extends therefrom into the interior of the said terminal, the said projection or finger being adapted to be engaged by a carrier as it approaches the said discharge opening, 5 whereby the said catch is disengaged from the said device to permit the latter to be opened by the impact of the said carrier.

5. A pneumatic despatch apparatus comprising a terminal having a discharge opening, a device extending across the said discharge opening to close the same, a catch, a weight connected with the said catch to hold the catch normally in engagement with the said device, a projection or finger extending 10 from the said catch into the interior of the said terminal, the said projection or finger being adapted to be engaged by a carrier as it approaches the said discharge opening, whereby the said catch is disengaged from the said 15 device to permit the same to be opened by the impact of the said carrier.

6. A pneumatic despatch apparatus comprising a plurality of terminals, each of which is provided with a discharge opening, devices 20 extending across the said openings to close the same, a catch which is normally out of engagement with one of the said devices, and a second catch which is normally in engagement with the other of said devices, each of 25 the said catches being provided with a projection or finger which extends directly therefrom into the interiors or passageways of said terminals, each of the said fingers or projections being adapted to be engaged by the forward end of a carrier as it approaches the said 30 discharge opening, whereby the first named catch is adapted to be moved into engagement with the closing device with which it is associated, the second catch being adapted 35 to be disengaged from the closing device with which it is associated.

7. A pneumatic despatch apparatus comprising a plurality of terminals, each of which is provided with a discharge opening, devices 40 extending across the said discharge openings 45

to close the same, catches adapted to engage the said devices to prevent the same from being opened, one of the said catches being normally out of engagement with its associated device, and the other of said catches being 50 normally in engagement with its associated device, a projection or finger extending from each of the said catches into the interior of the said terminals, carriers adapted to travel through the said despatch apparatus, one of the said carriers being provided with heads or enlargements upon its ends, the other of said carriers being provided with projections which are of greater length than the distances between the ends of the fingers which 55 extend into the interiors of the terminals and the inner surface of the closing devices and which projections are of less diameter than the adjacent portions of the carrier, the front or forward end of the first of the said carriers 60 being adapted to engage the projection or finger of the first named catch to occasion movement of the same to engage its associated device, and the said carrier being adapted to engage the projection or finger of 65 the second catch to occasion the disengagement of the same from its associated device, and a projection of the second named carrier adapted to strike the device for closing the discharge openings whereby if the catch which 70 is associated with a device is disengaged therefrom, the said device will be opened, and whereby if the said device is engaged by its associated catch, the forward end of the 75 said carrier will be deflected so as to prevent 80 engagement of the same with the finger of the said catch.

In testimony that I claim the foregoing as my invention I have hereunto signed my name this 22d day of June, A. D. 1905.

FRANKLIN S. SMITH.
